UNITED STATES PATENT OFFICE.

EDWARD B. MOSSER, OF PHILADELPHIA, PENNSYLVANIA.

DESIGN FOR STOCKING.

Application filed April 28, 1928. Serial No. 26,492. Term of patent 14 years.

To all whom it may concern:

Be it known that I, EDWARD B. MOSSER, a citizen of the United States, residing at Philadelphia, in the county of Philadelphia and State of Pennsylvania, have invented a new, original, and ornamental Design for Stocking, of which the following is a specification, reference being had to the accompanying drawing, forming part thereof.

Fig. 1 is a side elevation of stocking; Fig. 2 is a rear elevation of stocking; and Fig. 3 is an enlarged detail view of the design feature appearing down the back of the stocking as illustrated in Fig. 2.

I claim:

The ornamental design for stocking, as shown.

EDWARD B. MOSSER.
